UNITED STATES PATENT OFFICE.

ALBERT L. LAMBERT, OF NARBETH, AND ALFRED BELL, OF PHILADELPHIA, PENNSYLVANIA, ASSIGNEES TO AMERICAN MOTOR BODY COMPANY, OF PHILADELPHIA, PENNSYLVANIA, A CORPORATION OF DELAWARE.

WINDSHIELD.

1,417,076.

Specification of Letters Patent. Patented May 23, 1922.

Original application filed January 29, 1920, Serial No. 354,834. Divided and this application filed March 2, 1921. Serial No. 449,009.

To all whom it may concern:

Be it known that we, ALBERT L. LAMBERT, residing at Narbeth, in the county of Montgomery and State of Pennsylvania, and 5 ALFRED BELL, residing at Philadelphia, in the county of Philadelphia, in the State of Pennsylvania, both citizens of the United States, have invented certain new and useful Improvements in Windshields, of which 10 the following is a specification.

The invention covered by our present application is a division of our application Serial Number 354,834 filed January 29, 1920, for improvements in wind shields.

15 Our invention relates to an improved form of wind shield construction for automobiles, particularly those having closed bodies. The object of our invention is to produce a construction which will be extremely efficient 20 in operation, readily manufactured in large quantities and easily and accurately mounted in place and which will have various improved details of construction and combinations of parts.

25 The construction is particularly adapted, as stated, for use in connection with automobiles having closed bodies. When so used a pair of upright members are provided which are rigidly secured within the 30 right and left sides of the wind shield opening in the automobile body. These side frame members are of improved construction and are designed to take up variations in the opening and to make manufacturing 35 more convenient.

Upper and lower wind shields are pivotally mounted between the side frame members referred to so that the same will close in vertical positions and may be opened by 40 swinging each of the same at an angle to the vertical, and the particular feature of our invention covered herein relates to the use of a continuous wiping strip of rubber or the like on the face of each of the side 45 frame members, these strips extending continuously from the bottom of the opening to a point adjacent the top thereof. These strips are adapted to engage the side edges of both wind shields to make a tight construction when the shields are closed. Preferably the strips are so formed as to make 50 contact with each shield at two separated

points in different planes so as to make the shields doubly tight.

In order that our invention may be more 55 clearly understood, attention is hereby directed to the accompanying drawings forming part of this invention and illustrating one embodiment of our invention. In the drawings, Fig. 1 represents a front elevation of a construction embodying our invention mounted within the wind shield opening in a closed automobile, as viewed from the inside of the automobile, Fig. 2 is a vertical section taken on line 2—2 of Fig. 1, Figs. 3 60 and 4 are respectively horizontal sections taken on lines 3—3 and 4—4 of Fig. 1.

Referring to the drawings, the front 1 of the body of a closed automobile has an opening formed therein which is bounded at the 70 sides by portions 2, 2 of the body member 1.

Side frame members 3, 3 are provided and are adapted to be secured within the opening against the portions 2, 2 of the body at the sides of the opening. The side frame members 3, 3 may be described as generally channel-shaped in cross-section, the sections of the members varying, however, at different points in the height of the same. Members 3 are provided with flanges 4 which are 80 adapted to overlap the body members 2 at the front of the opening. Flanges 5 are provided, parallel to flanges 4, adjacent the inner edges of the openings, and flanges, or more properly speaking, web portions 6, connect outside and inside flanges 4 and 5 and 85 extend parallel to the edge surfaces of members 2, 2 but spaced inwardly of the opening, somewhat therefrom.

Members 3, 3 are rigidly secured in position within the opening by appropriate means such as screws 7, 7 which extend through the inside flange 6 of each member 3 and into the body portion 2 of the automobile. 90

The upper wind shield is provided with the usual glass panel 9 which is received in a suitable marginal frame 10. This is pivotally mounted adjacent its upper side edges, within the side frames 3, 3. Preferably, 100 trunnion members are provided, having L shaped flange portions 11 which are secured to the inner and outer faces of the sash or frame 10 at the upper corners thereof. Trunnions 95

12 are formed integral with the webs 11' connecting members 11 and are received within suitable seats in side frame members 3.

The upper wind shield may readily be 5 clamped either in its vertical, closed position, or in any position of oscillation of trunnions 12 within their bearings.

The lower wind shield is provided with a 10 glass panel 24 which is received within a marginal frame, the bottom portion of the same being shown at 25 and the side portions being indicated at 26. The upper and lower wind shields are adapted to extend in parallel planes, when closed, with the upper 15 edge of the lower shield and the lower edge of the upper shield overlapping.

The means for mounting the lower wind shield comprise members 31, 31 secured to the side frames 26 of the lower wind shield 20 and have pivot pins or trunnions 32 extending laterally, outwardly therefrom. Pivot pins 32 are rotatably mounted within blocks 33. A single strip 49, preferably formed of molded rubber, is secured to the 25 face of each member 3 and extends continuously from the bottom of the member 3 to the underneath side of the upper trunnion 12. Preferably each member 3 has a channel-shaped recess 50 formed in the face 30 of the web 6 thereof, the strip 49 being secured to member 3 within this recess. The strip is so positioned and so formed as to make a wiping contact with each of the wind shields when the latter are in closed 35 position. Preferably, the strip is provided with several projections thereon, one of which, 51, is directed away from the flange 6, that is inwardly of the opening. This flange makes wiping contact with the adjacent 40 edges of both the upper and lower shields where they overlap, and with the upper shield above this point and with the lower shield below this point. Strip 49 is also provided with flanges 52 and 53 which 45 extend at an angle toward the outside and the inside of the automobile respectively. The side rail of the upper wind shield is provided with a flange 10^a which is directed toward the flange 6 of member 3. The 50 side rail 26 of the lower wind shield is provided with a similar flange 10^b, and flanges 52 and 53 of the wiping strip 49 make contact with these flanges when the shields are 55 in their closed position. It will thus be noted that a pair of contact points are provided for each shield, these contact points being in different places so as to make both shields doubly tight.

What I claim is:—

60 1. In a wind shield, the combination of fixed side frame members having vertical channels therein, upper and lower wind shields pivotally secured to said members to extend between the same, said shields 65 extending in parallel planes when closed,

overlapping at their respective lower and upper edges, and continuous wiping strips mounted in said channels and extending substantially from top to bottom of said members, said strips being so formed and positioned as to make contact with the edges of both said shields when the latter are closed. 70

2. In a wind shield, the combination of fixed side frame members having vertical 75 channels therein, upper and lower wind shields pivotally secured to said members to extend between the same, said shields extending in parallel planes when closed, overlapping at their respective lower and upper 80 edges, said shields having marginal frames with side edge portions of angular cross section, such that a channel section is formed at the overlapping portions of the shields, and wiping strips mounted in said side 85 frame member channels and so formed as to make contact with the faces and flanges of the edges of both shields when the latter are closed.

3. In a wind shield, the combination of 90 fixed side frame members, a wind shield pivotally secured to said members to extend between the same and having a side rail with a side edge presenting two vertical surfaces disposed at an angle one to the 95 other, and a continuous vertical wiping strip secured to the face of one of said frame members, said wiping strip having two projections disposed at an angle one to the other and adapted respectively to contact against 100 one of said surfaces of said side edge of the shield when the latter is closed.

4. In a wind shield, the combination of fixed frame members having vertical channels therein, upper and lower wind shields 105 pivotally secured to said members to extend between the same, said shields extending in different parallel planes when closed, overlapping at their respective lower and upper edges, and a continuous wiping strip 110 mounted in one of said channels and extending substantially from top to bottom thereof, said strip having a vertical central projection adapted to contact the edges of both said shields when closed, and having 115 a second vertical projection on one side of said central projection adapted to contact said edge of one of said shields, when closed, at a distance from the place of contact of said central projection therewith, and having 120 a third projection on the other side of said central projection adapted to contact said edge of the other of said shields, when closed, at a distance from the place of contact of said central portion therewith. 125

5. In a wind shield, the combination of fixed side frame members, upper and lower wind shields pivotally secured to said members to extend between the same, each of said shields having a side rail presenting two 130

vertical surfaces disposed at an angle one to the other, and a continuous vertical wiping strip secured to the face of one of said frame members, said wiping strip having a central vertical projection adapted to contact simultaneously with one vertical surface of said side edges of each of the shields when the latter are closed, and having a vertical projection disposed at an angle to said central projection and on one side thereof adapted to contact the other surface of the side edge of one of said shields when closed, and also having a third vertical

projection disposed at an angle to said central projection and on the opposite side 15 thereof adapted to contact the other surface of the side edge of the other shield when the latter is closed.

This specification signed and witnessed this 28th day of February, 1921.
